DESIGN FOR A FIRE-SCREEN.

Design No. 14,171, dated August 14, 1883.

UNITED STATES PATENT OFFICE.

JAMES H. WHITE, OF NEW YORK, N. Y., ASSIGNOR TO MANHATTAN BRASS COMPANY, OF SAME PLACE.

DESIGN FOR A FIRE-SCREEN.

SPECIFICATION forming part of Design No. 14,171, dated August 14, 1883.

Application filed May 16, 1883. Term of patent 7 years.

To all whom it may concern:

Be it known that I, JAMES H. WHITE, of the city and State of New York, have invented a Design for a Fire-Screen, of which the following is a specification.

The base of the screen is quadrangular, having the leaflet and scroll feet *a* at the angles, with the scroll ornaments *b* and leaflet ornaments at *c*. Upon the base there are pedestals 10 having base-moldings *d*, and retiring elliptical surfaces *e*, ornamented with leaflets *f*, and above the molding *g* are the finials *h*, with radial leaflets and scrolls. The diverging frames 15 *k*, above the finials, are arched at the top and the surfaces ornamented with a zigzag figure with bands and leaflets in the triangles, as shown. The cap-piece above the arches of the frames has a circular ornamental base, *l*, to the handle *m*, the design of the handle being leaflets, scrolls, and a crown, *n*. Below the cap-piece are the pendants *r*, with the recessed-20 panel leaflets *s*. The plates of the screen are open lattice-work, as at *t*, and semicircular heads *u*, with open foliations, as shown.

25 I claim as my invention—

1. The design of the quadrangular base with the leaflet and scroll ornamental feet, scroll or-

naments *b*, and row of leaflet ornaments *c*, substantially as represented.

2. The design of the pedestals, consisting of 30 the base-molding, elliptical retiring surfaces, leaflet ornaments *f*, moldings, and finials *h*, substantially as represented.

3. The design of the diverging frames *k*, with arch top and cap-piece above the arch, sub- 35 stantially as represented.

4. The design of the ornamental base *l*, handle *m*, and crown *n*, substantially as represented.

5. The design of the pendants *r* below the 40 cap-piece, as represented.

6. The design of the open lattice work plates *t* and open foliated ornaments *u*, substantially as represented.

7. The design of the fire-screen, consisting of 45 the base, pedestals, frames, cap-piece, handle, pendants, and open lattice-work plates, substantially as described and represented.

Signed by me this 7th day of May, A. D. 1883.

JAMES H. WHITE.
